UNITED STATES PATENT OFFICE.

THOMAS H. CHURCHILL, OF TORONTO, ONTARIO, CANADA, ASSIGNOR OF ONE-HALF TO
JAMES SCROGGIE, OF TORONTO, CANADA.

CASTING-MACHINE.

No. 861,263.

Specification of Letters Patent.

Patented July 30, 1907.

Application filed March 1, 1906. Serial No. 303,624.

To all whom it may concern:

Be it known that I, THOMAS HOPE CHURCHILL, of the city of Toronto, in the county of York and Province of Ontario, Canada, have invented certain new and useful 5 Improvements in Casting-Machines; and I hereby declare that the following is a full, clear, and exact description of the same.

This invention relates to a casting machine comprising two separable groups of mold members, means for 10 accurately maintaining the mold members of one group relatively to the mold members of the other group, so that they will register in pairs when assembled and for collectively separating and bringing the mold members together, and an adjustable means for revolvably holding 15 the groups of mold members when assembled in either a horizontal or a perpendicular position, as hereinafter described and specifically pointed out in the appended claims.

For a full understanding of the invention reference is 20 to be had to the following description and to the accompanying drawings in which—

Figure 1 is a perspective view of a casting machine, with the mold members positioned to receive the rails and fillings. Fig. 2 is a perspective view of the same 25 machine shown in Fig. 1, with the molds in a vertical position and the groups of mold members closed together. Fig. 3 is a perspective view of the turn table and its hinge members for the molds shown in Figs. 1 and 2, but on a larger scale than in the preceding views and in 30 the same position as in Fig. 2. Fig. 4 is a section of the turn table and its hinge members on the same scale as in Fig. 3 and showing them in the same position as in Fig. 1. Figs. 5 and 5^a are perspective views of two 35 separated mold members. Fig. 6 is a view of part of the head or foot of a bedstead. Fig. 7 is a side view showing the cast joint of a rail and filling. Fig. 8 is an end view of the construction shown in Fig. 7.

Like letters of reference refer to like parts throughout the specification and drawings.

40 The casting machine illustrated in the accompanying drawings is hereinafter described in connection with the manufacture of metal beds and cribs, and the following description will be read with that purpose in view, but it can also be used for casting other articles of like nature, and is so arranged that it can be operated by inexperienced labor of ordinary intelligence to produce the finished product.

The group of mold members *a* are selectively arranged on and fastened to a rigid mold frame *b* and the mold 50 frame *b* is revolvably connected to a hinge member *d*. Hinged to one side of the mold frame *b* is a corresponding mold frame *e* and fastened to the mold frame *e* are mold members *f* positioned to register with the mold members *a* when the mold members are closed together.

The mold members *a* and *f* as shown in Figs. 5 and 5^a, 55 are formed with matrices for the rails and fillings of the bed shown in Fig. 6, and when the mold members *a* and *f* are assembled, they constitute the molds for casting the joints of the rails *h* and fillings *i* shown in Figs. 7 and 8. The matrices *j* for the rails *h* are arranged, in 60 the mold members, lengthwise of the frames *b* and *e* and the matrices *k* for the fillings *i* are arranged at right angles to the length of the frames and extend from the matrices *j* to the inner sides of the molds. At the junction of the matrices *j* and *k* are matrices *l* for the eyes *l'* 65 of the fillings.

In assembling the parts for the construction shown in Fig. 6, the fillings *i* are placed in the matrices *k* with the eyes *l'* contained in the matrices *l* and the rails *h* inserted through the eyes *l'* and contained in the matrices *j*. The mold members are then closed together and the groups of mold members are securely locked in their closed position to retain the rails and fillings in their relative places in the molds.

Formed through the molds to the matrices *l* are ingates *m* through which the molten metal is introduced into the matrices, the ingates and matrices being so formed as to direct the metal to the sides of the eyes *l'* and around the rails.

The mold members *a* for forming the cast joints of 80 those structures comprising two rails and fillings with eyes for each rail are arranged in two separated groups on the mold frame *b* and so positioned thereon that they will hold the fillings at right angles to the rails during the casting of the joints, and the mold members 85 *f* are arranged in corresponding groups on the mold frame *e* so that they will register with the mold members *a*. When the mold frame *e* is raised into the position shown in Fig. 1, it will lift the mold members *f* collectively away from the mold members *a* and when 90 it is moved into the position shown in Fig. 2, it will bring the mold members *f* collectively into position to register with the mold members *a*. In the operation of this part of the apparatus, the mold frame *e* is moved into the position shown in Fig. 1, and the parts to be 95 joined, viz., rails and fillings, are placed in position in the matrices of the mold members *a*. This arranges all the fillings at right angles to the rails and spaces them at their selective distances from each other. When this part of the operation is completed the mold 100 frame *e* is lowered towards the mold frame *b* to bring the mold members *f* collectively into position with the mold members *a*, and the two mold frames are then locked together by suitable fastening means *o*. The mold members *a* while the rails and fillings are being 105 positioned, lie in a horizontal plane in which it would be impracticable to pour the molten metal into the molds when the mold members are closed together.

and it is therefore necessary to so arrange the apparatus that the molds can be turned from the horizontal position shown in Fig. 1 to the vertical position shown in Fig. 2, and this is accomplished by providing the 5 mold frame *b* with a turn table *c* pivotally connected to a hinge member *d* and articulately connecting the hinge member *d* to a hinge member *p* fastened to or forming part of the machine frame *q* and at one end thereof. When the molds are in the horizontal position 10 shown in Fig. 1 or moved into the vertical position shown in Fig. 2, they can freely revolve collectively by means of the turn table without coming into contact with the machine frame. The ingates *m* of each 15 row of molds are so located that when one row of molds is turned into the position shown in Fig. 2, the ingates will be uppermost to permit of the molten metal being readily poured therein to enter their matrices *l* and when that has been done the turn table and mold frames are revolved to bring the other row of molds 20 into the position occupied by those first mentioned, so that the molten metal can be poured through the ingates *m* into the matrices of the second row of molds. By the use of this apparatus it is possible for inexperienced labor to join the rails and fillings of the sides 25 and ends of a crib or the head and foot of a bedstead quickly and without any reasonable possibility of making a mistake in the joining operation.

The above described construction is designed for the manufacture of that class of bedsteads and cribs in 30 which both ends of the fillings are to be joined to the rails.

Having thus fully described my invention what I claim as new and desire to secure by Letters Patent is;

1. A casting machine comprising a set of molds consisting of two groups of separable mold members, means for maintaining the groups of mold members relatively to each other, and for collectively separating and bringing them together; means for moving the molds into horizontal

and vertical positions, and means for collectively revolving the molds in their horizontal and vertical positions. 40

2. A casting machine comprising a mold frame, a group of mold members selectively arranged thereon, a second mold frame articulately connected to the first mentioned mold frame, a group of mold members selectively fixed to the last mentioned mold frame and collectively carried 45 thereby to register with the first mentioned mold members, means for revolvably holding said frames and molds and other means to permit said frames and molds to collectively move into a vertical or a horizontal position.

3. A casting machine comprising two separable groups 50 of mold members, means for accurately maintaining the mold members of one group relatively to the mold members of the other group, so that they will register in pairs when assembled and for collectively separating and bringing the mold members together, and means for revolvably holding the groups of mold members when assembled in either a horizontal or a vertical position.

4. A casting machine comprising a set of molds, a supporting means for the molds movable from a horizontal to a vertical plane, and means for revolvably connecting the 60 molds to the supporting means.

5. A casting machine comprising a set of molds, a supporting means for the molds comprising a stationary supporting member and a movable supporting member hinged to the stationary member and capable of being moved from 65 a horizontal to a vertical plane, and means for revolvably connecting the molds to the movable supporting member.

6. A casting machine comprising a set of molds consisting of two groups of separable mold members, means for 70 collectively separating and bringing the groups of mold members together, a supporting means for the molds comprising a stationary supporting member, and a movable supporting member hinged to the stationary supporting member capable of being turned into a horizontal or into a vertical plane; and means revolvably connecting the molds with the movable supporting member to permit of their revolution when the movable supporting member is in either its horizontal or its vertical position.

Toronto, February 24th, A. D. 1906.
